Primary Examiner — Dana K Weiland*Assistant Examiner* — JennyLou M Binas(74) *Attorney, Agent, or Firm* — Maschoff Brennan(57) **CLAIM**

I claim the ornamental design for a vacuum cleaner, as shown and described.

DESCRIPTION

FIG. 1 is a perspective view of a vacuum cleaner showing the new design;

FIG. 2 is a front elevational view thereof;

FIG. 3 is a rear elevational view thereof;

FIG. 4 is a left side, elevational view thereof;

FIG. 5 is a right side, elevational view thereof;

FIG. 6 is a top plan view thereof; and,

FIG. 7 is a bottom plan view thereof.

The dotted lines and dashed broken lines in the drawings depict portion of the vacuum cleaner that form no part of the claimed design.

1 Claim, 6 Drawing Sheets(56)
